UNITED STATES PATENT OFFICE.

LOUIS A. KRAMER, OF CHICAGO, ILLINOIS.

DEHAIRING MECHANISM.

Application filed March 27, 1922. Serial No. 546,960.

To all whom it may concern:

Be it known that I, LOUIS A. KRAMER, citizen of the United States, residing at Chicago, in the county of Cook and State 5 of Illinois, have invented certain new and useful Improvements in a Dehairing Mechanism; and I do hereby declare the following to be a full, clear, and exact description of the invention, such as will enable 10 others skilled in the art to which it appertains to make and use the same.

My invention relates to carcass dehairing and cleaning machines, and in its general aspects aims to provide improved arrangements of the dehairing means and the carcass conveying means, as well as improved arrangements for suitably spacing these two sets of means and preventing them from interfering with one another:

20 In one important aspect, my invention relates to the construction of rotating means for dehairing, scraping and polishing carcasses, and in this aspect aims to provide rotatable cleaning members which will be unusually effective in operation, which will exert increased pressure when encountering resistance, which will readily adjust themselves to desirable positions, which will permit a choice of various desirable materials 25 for certain portions thereof, and which will easily permit of the replacing of any worn parts.

In another aspect, my invention relates to carcass conveyers and aims to provide a 30 novel construction of the push arms of such conveyers to increase the effectiveness of the thrust and to prevent a resistance to the pushing movement from kinking the conveyer chain to an undesirable extent.

40 Furthermore, my invention also aims to provide simple and effective means for spacing the rotating cleaning members from the conveyers and from the push arms mounted on the latter, so as to prevent any portion 45 of the cleaning elements from engaging the conveyer chains, and also aims to maintain the dehairing elements in proper operative position while employing unusually simple mountings for the same.

50 Furthermore, my invention aims to provide a mounting for a dehairing element of the socalled beater type which will afford a thrust-effecting backing for each of the flexible beaters and in which the thrust elements will be so arranged as to prevent the

accumulation of hair or other deposits upon the mounting for the same.

Still further and also more detailed objects will appear from the following specification and from the accompanying drawings, in which

Fig. 1 is a longitudinal section through a carcass dehairing machine of the general type shown in U. S. Patent No. 1,336,524, as issued to me on April 13, 1920, showing 60 the arrangement of portions adjacent to the delivery end of the machine and showing a machine of this type as equipped with various features of my invention.

Fig. 2 is an enlarged and fragmentary 70 longitudinal section through the same machine taken from immediately in front of one of the conveyer chains and showing my novel arrangement of the thrust arms for the conveyer.

Fig. 3 is a fragmentary section through the machine taken at right angles to Figs. 1 and 2 and showing the relative positions of certain conveyer portions and of the beater members between which the conveyers 80 travel.

Fig. 4 is a perspective view of one of the thrust arms and of the adjacent links of the conveyer chain.

Fig. 5 is an enlarged transverse section 85 through the type of beater member illustrated in Fig. 1, namely a section taken transversely of its axis through the center of the beater member or along the line 5—5 of Fig. 3.

Fig. 6 is a perspective view of the same beater member with all except two of the pairs of beater arms detached and with the drum flange nearest to the observer cut away to show the arrangement of the other parts. 90

Figs. 7 and 8 are sections similar to portions of Fig. 5 and showing other arrangements of the springs used in connection with the mountings of the beaters.

Fig. 9 is a somewhat similar section showing another mounting of the beaters, namely one in which no spring is employed.

Fig. 10 is a section similar to Fig. 5, showing a beater carrier including a drum having a scalloped cross-section.

Fig. 11 is a perspective view of the beater member of Fig. 10, with the nearer flange cut away and with all except two of the beaters detached.

Illustrative of my invention, I am pictur-

ing and describing the same as applied to a carcass cleaning machine of the general type shown in my said U. S. patent, although I do not wish to be limited to the 5 use of the various features of my invention in connection with any particular type of machine or in combination with one another. In the drawings, Figs. 1, 2 and 3 show portions of a machine of the said type, 10 in which the frame 1 supports a series of parallel shafts 2 extending transversely of the machine and all rotated by power in a direction which is clockwise in Fig. 1. Each of these shafts has a plurality of 15 beater members fastened upon the same. These beater members are spaced from each other to permit conveyer chains 3 to pass between them towards the right of Fig. 1 but at a rate which is slow relative to the 20 rate at which the outer portions of the beater members are moved. Each beater member comprises a supporting portion or carrier substantially in the shape of a drum, and including a hub 4 fastened to the shaft, 25 a side flange 5, and rigid webs connecting the flanges and supporting the beaters proper.

Each of the beaters mounted on the carrier desirably consists of a flexible or strap member 6 secured near its inner end to one of the said webs and extending outwardly of the drum, together with a plurality of steel scrapers which desirably include an end scraper 7 fastened near the outer end 30 of the beater strap 6 and a companion scraper 8 fastened near the inner end of the strap, both of the scrapers on each strap being curved somewhat into a hook formation convexed towards the direction in which 35 the scrapers move when the beater member is in operation. In my said issued patent, I have shown these beater members as extending tangentially of the cylindrical portion of a drum to which they are fastened 40 and as adapted to be pressed against this cylindrical drum portion by engagement with a carcass so as to barely project beyond the flanges of the drum. I have also shown the beaters as equipped with scrapers 45 so located on the beater straps as to interfere with a direct contact of these straps with the carcasses, the latter being shown as hogs since the general type of machine to 50 which my invention relates is most commonly employed for the dehairing, cleaning and polishing of hogs.

In operating the machine of my said patent, I found that a greater reach of the beaters beyond the drum flanges would be 55 desirable both for effective scraping, for assisting in a rotating of the hogs, and for permitting portions of the beater straps to engage the hogs so as to afford a massaging and polishing effect on the said hog. I have 60 also found that while this greater reach

and direct contact of the beater strap with the hog is desirable when the hog is in certain positions, it is desirable to have the scrapers exert a more effective pressure than they can do if this pressure is largely dependent on the velocity imparted to the beaters by the rotation of the drums carrying the same. To attain these desirable effects, I mount the beater straps so that they will normally extend in directions which are not substantially tangential of the drum flanges, but which more nearly approach positions midway between such tangential directions and radial directions. Then instead of employing a cylindrical drum against which the beaters can be flexed by the weight of the hog and the resistance of the latter to the action of the beaters, I back the strap portion of each beater with a web which extends longitudinally of the beater carrier or drum between the flanges thereof and which is convexed towards the beater strap. In practice, each of these webs desirably has a cross-section which is of a substantially cycloidal contour and which has its outer end spaced from the axis of the drum by a distance approaching, but somewhat less than, the radius of the drum flanges. Then I desirably employ beater straps presenting exposed portions which normally extend beyond the periphery of the drum flanges so as to permit of their direct engagement with the hogs in certain positions of the latter, as illustrated for example in connection with the hog C shown in dotted lines in Fig. 1.

The beater strap itself may be made of a variety of materials, although I desirably employ a material which is flexible without being too freely so. Then instead of depending entirely on a bending of the strap for permitting the needed movement of each beater with respect to the drum carrying the same, I may mount each strap so as to permit a bodily rocking of the same on the web back of the strap, and may employ spring means for resisting such rocking movement. For example, Figs. 1 and 5 show beater members in which each web 9 has an inner portion affording a substantially flat surface to which the beater strap 10 is fastened and which flat surface is disposed at an angle of approximately 45 degrees to the radius leading from the fastening point of the strap to the axis of the drum. I am also showing this web as continued outwardly in the form of a curve presenting a convexed surface towards the strap and terminating substantially concentric with the periphery of the drum flange 5 but somewhat inward of the latter. Then I am showing each beater strap 10 as sufficiently resilient to resist a bending of the same close for its

entire length along the adjacent surface of the web 9, so that the inner end of the strap will tend to swing rearwardly and outwardly when an encountered hog offers 5 a considerable resistance to the outer hook 11 on the strap.

To permit of such a bodily rocking movement for the strap, I desirably secure the strap to the web 9 by a bolt 12 which has 10 spring means associated with it for resisting the said movement. For this purpose, Fig. 5 shows compression springs 13 as interposed respectively between the bolts 12 and the rear faces of the webs 9, thereby permitting 15 the said rocking tendency of the beater strap to compress the spring and to slide the fastening bolt forwardly after the manner shown in connection with the uppermost beater in Fig. 5. Furthermore, I am showing each strap as 20 having associated with it an inner scraper 14 which is mounted on the same bolt 12 between the inner end of the strap and the fastening bolt, so that the same 25 rocking movement of the strap will move this inner scraper radially outward of the drum or into a position in which it will be more likely to reach parts of the hog projecting between the flanges of the drum, as 30 for example the legs of the hog.

However, it is not imperative that the spring employed in connection with the fastening of each beater strap should be of a spiral compression type, or that it should 35 be disposed behind the thrust-receiving web. For example, an arched flat spring 15 might be employed behind the web after the manner shown in Fig. 7. Or, the strap (if of a suitable grade of steel) might be doubled 40 back upon itself in front of the web as in the case of the strap 30 shown in Fig. 8.

With each of these arrangements as pictured in Figs. 5, 7 and 8, I desirably do not extend the thrust-receiving webs inwardly 45 all the way to the hub of the drum, but preferably space these webs from this hub by a considerable distance, so as to afford spaces through which the hair, nails, dirt or other scrapings can pass out. By so doing, 50 I avoid the gathering of refuse in the drum and the clogging of the springs or the like by such refuse, as the action of centrifugal force will continuously tend to throw any such refuse out through one or another of 55 the openings. Moreover, the water which is commonly sprayed upon the hogs during the operation of the machine will also flush any refuse through these openings so as to carry the same down upon the screen 15, 60 from which screen the refuse is then pushed towards the left of Fig. 1 by the thrust arms 16 of the conveyer, while the water drips through the perforations 17 of the screen.

However, I do not wish to be limited to 65 the use of a resilient material for the straps,

nor to the provision of such spaces between the thrust-receiving webs and the hubs of the beater drums. For example, I may continue the curving of each web inwardly from its outer end until it meets the inner end 70 of the web back of the same, thereby affording the scalloped cross section of the drum 18 of Fig. 10. So also, I may omit the spring arrangements, such as those here- 75 fore described in connection with Fig. 5, and may employ a more flexible beater strap made of leather or of a rubberized fabric, in which case the inner end of the strap is rigidly fastened to the drum 18 by a bolt 20 as shown in Fig. 11. Or, I may extend the inner end of each web substantially 80 radially of the drum until it connects to the hub, after the manner of the web 21 of Fig. 9.

In each case, I desirably make the beater 85 straps long enough so that an exposed portion of the same will normally extend outwardly beyond the drum flanges, as shown both in Fig. 5, and in Figs. 7 to 10 inclusive, and I desirably allow the outer scraper 11 to project for some distance beyond the outer end of the strap. By so doing, I am able to secure the long effective reach of the outer scraper as shown in connection with the hogs A and C of Fig. 1, which long 90

reach assists in rotating the hogs so as to make sure that all substantially surface portions of the same will be cleaned in a single passage through the machine. By so doing, I also profit by the massaging and polishing effect which is secured by a direct contact of the hog with strap portions, as shown in connections with hogs B and C. Furthermore, it will be obvious from Figs. 5 and 10 and from the beater member engaging the 100 hog B of Fig. 1 that the web back of each beater strap resists a flexing of the strap to an increased extent as the resistance of the hog to the beater increases. Consequently, I am able to utilize the weight of the hog 105 for increasing the pressure with which the scrapers engage the surface of the hog whenever the latter is in certain positions, which positions rapidly recur, owing to the gradual travel of the hog and the rotation of 110 the beater members. However, by properly proportioning the distance at which each thrust-resisting web terminates radially inward of the adjacent drum flanges, I can readily limit this pressure to a degree which 115 will not tear or otherwise damage the hog.

To move the hogs past the beater members in proper position for an effective de- 120 hairing and cleaning action, I desirably follow the practice of my said patent by mounting beams 22 longitudinally of the machine, each beam having a notch 23 which straddles the hubs of two of the beater drums on the same shaft, and each beam carrying at its top an upwardly open steel 125

channel 24. Each such channel serves as a guide for one of the conveyer chains 2 which support the hogs during their travel, and which chains have thrust arms 25 spaced 5 along them to limit the rolling of the hog upon the chains and to aid in resisting the pressure of the beaters. Each such thrust arm 25 desirably has at its tip a collar 26 to prevent a hog from being rolled over the 10 top of the arm, as more fully described in my said patent. In practice, I have found that when a hog is in a position in which the beater would tend to roll it up along an adjacent arm, as in the case of the hog B 15 of Fig. 1, the leverage afforded by the height of the arm tends to kink the conveyer chain to an extent which is undesirable because of the undue tightening and straining effect on the chain. To overcome 20 this objection, I desirably provide each thrust arm 25 with a pair of fingers 27 extending both longitudinally and transversely of the link carrying the thrust arm and overhanging the chain links 28 between 25 which this arm 25 is interposed, after the manner shown in Figs. 2 and 4. By so doing, I greatly extend the effective length of the base of the arm, so that I reduce the leverage due to the above described effect 30 and prevent an overstraining of the chain.

To simplify the construction and to permit some freedom of movement for the beaters, I desirably employ only a single bolt for fastening each beater strap, after the manner shown in Fig. 6, although the inner scraper 14 may be of such a length that it can extend across both of two beater straps mounted alongside each other on a correspondingly wide web 9. By employing such 40 a mounting with some space longitudinally of the drum between the two beater straps and between each beater strap and the adjacent drum flange, I permit a limited amount of rocking of the straps about the fastening 45 bolts 12 as pivots. In practice, I have found that this play is not objectionable but rather permits each beater to adjust itself more effectively to the position momentarily needed for action on some part of the irregular 50 contour of the hog. By arranging the drum flanges as illustrated, I cause these to limit the lateral swinging of the beaters, so that I can readily prevent their engaging the thrust arms 25 even though the chain carrying the 55 latter may have ample lateral play in the guide channel 24 to avoid undue friction. Consequently, my said arrangements of the conveyer parts and beater mountings cooperate in affording an unusually effective 60 cleaning action without the risk of any interference between the beaters and any portion of the conveying mechanism.

However, while I have illustrated and described my invention in embodiments includ- 65 ing various highly desirable features, I do

not wish to be limited to the details of the construction and arrangement thus disclosed, as these might obviously be modified in many ways without departing from the spirit of my invention or from the appended 70 claims. For example, I do not wish to be limited to the materials which I have mentioned, nor to the mounting of two beaters on each web, it being evident for example that a single and correspondingly wider 75 beater might be employed, such as the one illustrated in Fig. 11.

I claim as my invention:—

1. A rotatable dehairing member comprising a hub, a pair of end flanges fast thereon, a plurality of beater carriers spanning the flanges and having beater-engaging surfaces convexed forwardly with respect to the direction of rotation of the dehairing member, and flexible beating members respectively secured to the forward surfaces of the said beater carriers, the beater carriers being freely spaced from the hub to permit hair or the like to pass therebetween. 85

2. A rotatable dehairing member comprising a beater carrier, a plurality of flexible beaters disposed radially of the axis of the carrier and secured to the latter at their inner ends, and presser members respectively disposed behind the beaters and each presenting towards the adjacent beater a surface convexed about an axis parallel to but spaced from the axis of the holder, each such surface being of such a length as to adapt it for engaging the adjacent flexible 100 beater for substantially the entire length of the latter, the carrier including a hub and each presser member being freely spaced from the hub to afford a passage for the ejection of hair or the like. 105

3. A dehairing device comprising a rotatable carrier having webs symmetrically disposed about its axis, resilient beaters respectively mounted at their inner ends on the webs, and yielding means associated with the said mounting of the beaters to the webs for permitting a limited bodily movement of the inner beater ends away from the webs on which they are mounted. 110

4. A dehairing device comprising a rotat- 115 ing carrier having a web extending out- wardly of the axis, a pin transverse of the web at a distance from the outer edge of the latter, a beater extending substantially radi- ally of the device and having one end slid- 120 able on the pin, and yielding means urging the said inner end towards the web.

5. A dehairing device comprising a rotat- 125 ing beater carrier, flexible beaters each se- cured at its inner end to the carrier and each normally extending substantially radially of the carrier beyond the latter, the carrier hav- ing portions behind the beaters for defining the bending of the beaters when forcibly en- 130 gaging a carcass adjacent to the same, each

beater being secured to the carrier at its inner end by yielding means which permit the said end of the beater to move away from the carrier when the outer end of the beater

5 engages a carcass.

6. In a carcass dehairing machine, a carcass conveyer comprising endless chains and thrust arms mounted on spaced links of each chain, each thrust arm having a base extending in both directions longitudinally of the chain beyond the link on which the arm is mounted, so as to overhang and rest upon the links adjacent thereto.

7. A carcass conveyer for a dehairing machine, comprising a chain composed of central link members alternating with pairs of lateral link members, and thrust arms carried by certain of the central link members,

each thrust arm being widened at its base to overhang and rest upon the two pairs of 20 lateral link members between which the link carrying the thrust arm is disposed.

8. In a carcass dehairing machine, a carcass conveyer comprising endless chains, and thrust arms mounted on spaced links of each 25 chain, each thrust arm having a base extending in both directions longitudinally of the chain beyond the link on which the arm is mounted, so as to overhang and rest upon the links adjacent thereto, the said base extending close to the said two pairs of lateral links beyond the ends of the link carrying the thrust arm.

Signed at Chicago, Illinois, March 24th, 1922.

LOUIS A. KRAMER.
